UNITED STATES PATENT OFFICE.

STEPHEN McCLELLAN, OF BROOKLYN, NEW YORK.

LEVER MOTOR-POWER.

No. 797,307.

Specification of Letters Patent.

Patented Aug. 15, 1905.

Application filed April 12, 1904. Serial No. 202,766.

To all whom it may concern:

Be it known that I, STEPHEN McCLELLAN, a citizen of the United States, residing at Brooklyn, in the county of Kings and State of New York, have invented certain new and useful Improvements in Lever Motor-Powers, of which the following is a specification.

My invention is a lever motor-power.

My invention relates to that class of motor-powers in which the lever is used in connection with a combination of sprocket or friction ratchet-wheels which work on the hub of the gear-wheels and are connected to oscillating wheels and lever by either a rope, strap, band, or sprocket-chain, and in the further description of the motor I will only refer to the sprocket-chain; but I do not confine myself to this alone for transmitting the power from the oscillating wheels to the friction ratchet or sprocket ratchet wheels and the gear-wheels, but can use any other of the above-mentioned rope, strap, or band if I find it desirable to do so.

The following is a full and clear description of the motor as applied to the running-gear of a road-wagon or machine in double form and also a description of it in single form and the manner of operating the same.

In the accompanying sheets of drawings, Figure 1 is a perspective view of my invention. Fig. 2 is a partial top plan view, partly in section. Fig. 2^x is a cross-sectional view of Fig. 2 on the line 2^x 2^x. Fig. 3 is a side elevation of my invention in modified form. Fig. 4 is a partial top plan view of my invention as shown in Fig. 3. Fig. 5 is a take-up clamp for tightening the sprocket-chain, belt, or band. Fig. 6 is a vertical sectional view of the upper end of the combined lever and guide. Fig. 7 is a vertical view of the combined lever, showing a modified form of my device for locking either one of the oscillating wheels.

Fig. 1 shows my invention in what I call "double" form—that is, there are two exact duplicate sets of the oscillating wheels and of the sprocket ratchet-wheels and of the gear-wheels and sprocket-chains which are preferably used in this form when the machine, boat, or wheeled vehicle of any kind is propelled both forward and backward; but I am not confined to this double form of these parts to accomplish this purpose. In Fig. 3 the motor is shown in single form that is also used and operated in both directions, if desired.

Referring again to Fig. 1, 1 is a rectangu-

lar frame which supports the motor mechanism and the axles and their wheels and also the body of the road-wagon, tricycle, or other wheeled machine, as only one wheel could be used on the front axle to support and guide the machine that I show in Fig. 1, if desired, without any material change in the general construction of the framework. The body is not shown in Fig. 1, but may be of any suitable design. 2 is the front main axle of the wagon, and 2^a is the rear axle. The front axle is pivoted to cross-bar 1^a of the frame 1 at its center by king-bolt 3, which is rigidly fixed in axle 2, passing up through the cross-bar 1^a in frame 1 and also up through the bottom of the front end of the wagon-body, (not shown,) and passing crosswise through the head of the king-bolt near its top is a bar 3^a. The wheels 4 on the front axle turn loosely on the same, as on ordinary wagons, and may be fitted with ball-bearings. Rear wheels 4^a on rear axle 2^a are provided on their ends of hub 4^b on the inside with a slightly-enlarged part 4^c, which has near its center a lug 4^e cast on it, through which a chisel-pointed ratchet-stem 4^d works, the said ratchet-stem being operated by its coil-spring 4^e, (see Fig. 2^x.) said chisel-point of ratchet-stem 4^d fitting either right or left, parallel with, and in grooves in the ratchet-projected body 5 of the gear-wheel 5^a. The said-gear wheel 5^a is preferably fitted with ball-bearing on axle 2^a, working loosely on same between the two side bars of the frame 1 and is kept up against the said bars by the supporting-strap 1^b, fastened rigidly to said axle 2^a between said side bars, and at its outer end riveted or bolted to cross-bar of frame 1 and supports frame 1 and keeps the edges of holes 1^c so that the ratchet-body 5 of gear-wheel 5^a passes out through without touching the edges of said holes, thereby not creating any friction against it. It will be proper to state here that this gear-wheel 5^a has a duplicate or mate fitting against the opposite side bar on the other side of strap 1^b, working on axle 2^a the same way, and that the other two gear-wheels with their ratchet sprocket-wheels and the oscillating wheels hereinafter mentioned each have their exact duplicate wheels working on their axles against the opposite side bar the same as they do. Gear-wheel 6 works on its axle 6^a, which has a shoulder formed to fit up against its inside end, keeping it up against the inside of the frame, and works loosely on its axle 6^a. It also has a ratchet-body 6^b projecting from its center encircling its axle 6^a,

and on this ratchet-body is fitted sprocket-ratchet-wheel 6^c, which has a chisel and ratchet-stem 6^d passing down through its hub 6^e and fitting in grooves in ratchet-body 6^b and operated and held in same by its spring practically the same as the ratchet in the hub of wheel 4^a above described. (See Fig. 2^x.) Gear-wheel 7, its axle 7^a, its ratchet-body 7^b, its sprocket-wheel 7^c, ratchet-stem 7^d, and spring, is an exact duplicate of gear-wheel 6. The gear-wheels 5^a, 6, and 7 are all situated on their axles so that their gear-teeth around their outer rim all mesh with each other, so that when one is revolved they all revolve. Sprocket-wheel 8 on its axle 8^a is so situated in its alinement that it holds the sprocket-chain 12 up against the under side of ratchet sprocket-wheel 7^b and causes it to catch on its sprocket-teeth and operate it, as would be seen if this were not used. When all the gear and oscillating wheels were used on a direct line, as shown in Fig. 1, the chain 12 would drop away from the under side of sprocket-wheel 7^b and would not turn it; but the oscillating wheels might be placed in a position almost directly over said sprocket-wheel 7^b, in such a position that this extra sprocket-wheel 8 might be dispensed with, so I do not confine myself to its use. Oscillating wheel 9 works on its axle 9^a, preferably on ball-bearings, and has a groove of suitable width for the sprocket-chain to fit in. One side of oscillating wheel 9 is cut away at 9^b, having the small friction wheels or rollers 9^c and 9^d fitted near the points where the cut-away portion 9^b begins on either side. The take-up clamp 10, used to tighten the chain, is located in this cut-away part of said oscillating wheel. Near the upper part of oscillating wheel 9 there are several slots 9^f in its body for the purpose of allowing the lock-bar 11 to drop in that fits in slot 11^a of the lever 11^b and is pivoted in said slot by a lever or crank handle 11ⁿ and is used to lock lever 11^b to either of the oscillating wheels 9 by being thrown into one of the slots 9^f by a bolt transversely secured to said lever 11^b, and by a crank or lever α said bolt may be pushed into holes or slots 9^f near the top part of said oscillating wheels 9, (see modification, Fig. 7,) so I do not confine myself to this lock-bar 11. The hub 11^c of the lever 11^b also works on the axle 9^a of oscillating wheels 9 and fits snugly up against the inside of said oscillating wheels 9, keeping them in place up against the side frames of the frame 1 and also separating them. Just above the slot 11^a a shoulder 11^d is formed around the lever 11^b, and from the upper edge of this shoulder 11^d the stem of lever 11^b is round. Below this shoulder 11^d, down to its hub 11^c, it is preferably square if used with slot 11^a and lock-bar 11, as described above. On the round stem of lever 11^b, above the shoulder 11^d, a short cylinder 11^e fits snugly, but can be revolved, and two arms 11^f project

from its sides near its lower end. On its upper end notches 11^k are formed. Just above the cylinder 11^e another cylinder 11ⁱ fits on the cylinder 11^e of lever 11^b and has on its lower end projections 11^j, that fit in notches 11^k of cylinder 11^e and bind them together when in use. At the top of cylinder 11ⁱ are handles 11^l, that project from its sides. On the arms 11^f of cylinder 11^e two arms 11^g are pivoted, and through their outer ends slots 11^h are formed, and through these slots a cross-bar 3^a in the top of king-bolt 3 passes. Each end of the sprocket-chains 12 is fastened to the ends of the take-ups 10. Rollers 9^e on oscillating wheel 9 then pass over the top of the ratchet sprocket-wheel 6^c, that works on the ratchet-body 6^b of the gear-wheel 6, then returns back under the ratchet sprocket-wheel 7^c, that works on the ratchet-body 7^b of gear-wheel 7, thence up over the sprocket guide-wheel 8, and down under the lower edge of oscillating wheels 9 to the lower end of take-up 10 at friction-wheels 9^a.

To operate my machine, the operator would take his seat, situated on the body of the wagon just rearward from the lever, (not shown in drawing,) and then if he wanted to move the machine forward he would first, by the use of the lever or crank-handle 11ⁿ, throw the lock-bar 11 into one of the slots 9^f in the oscillating wheel 9, that is on the right-hand side of the lever 11^b. This locks lever 11^b to the said right-hand oscillating wheel 9. Then by pushing and pulling on said handles 11^l backward and forward, moving the chain 12, which in turn moves the ratchet sprocket-wheels on the gear-wheels 6 and 7, which by reason of their meshing together in their cog-rims and with gear-wheels 5^a cause it (cog-wheel 5^a) to turn, and its connection with the right-hand wheel 4^a by its ratchet forces it to turn, which moves the wagon forward. The ratchet-plungers in the ratchet sprocket-wheels on gear 6 and 7, being set reverse from each other, the one on gear 7 locking as the lever is pushed forward, thereby causing gear-wheels 7 to turn forward, and it in turn by its cog connection with gear-wheel 6 making it (the said gear-wheel 6) turn backward, and it by its cog connection with gear-wheel 5^a causing the said gear 5^a to turn forward, which wheel 4^a being locked to the said gear-wheel 5^a by its ratchet connections travels with it. The backward movement of the wagon is gotten by throwing lock-bar 11 to the left into one of the slots in the left-hand oscillating wheel 9, the ratchets in gear-wheel 5^a, 6, and 7 being set in the opposite direction to the one just described for the forward motion. By the operator moving the lever just as he did before backward and forward he propels the wagon backward, and to guide the machine or wagon he simply turns the handles 11^l, which in turn turns both the cylinders 11^e and 11ⁱ, which move the arms 11^g,

which turn the front axle 2 by reason of their connection with the king-bolt 3, cross-bar 3^a, provided with shoulders 3^b, so that the operator can at the same time he is operating the machine either backward or forward guide the same by the same lever.

It will be seen by the peculiar arrangement of my motor-power that there is absolutely no dead-center to overcome, as the machine will move instantly either forward or backward by the slightest movement of the lever. The only lost motion in it would be what is usually lost in a sprocket chain or belt connecting or running power.

The backward movement of my machine can be used when going downgrade as a brake, and the arrangement of the ratchet sprocket-wheels on gears 6 and 7 to either turn with them or stand still by their ratchet-plunger slipping over the grooves or teeth of the said ratchet-heads on the said gears 6 and 7, so that the machine when it has momentum enough to run without the operator working the lever going downgrade the sprocket wheels and chain and oscillating wheels and lever can stand perfectly still, unless he should want to use the backward motion just as a brake. This is a valuable point in my machine, as it would be objectionable to have them turning when not needed. The gear-wheels 5^a, 6, and 7 would turn with the wheel 4^a on the right-hand side if the machine were still set for the forward motion; but the ratchet-wheels on 6 and 7, the chain, and the oscillating wheels would stand still, and on the left hand all the wheels except the wagon-wheels 4 and 4^a would stand still, as the ratchet in the hub of left-hand wheel 4^a would allow it to turn forward without its turning its connecting gear-wheels 5^a, as its ratchet is set to slip when going forward.

The gear-wheel 5^a can be used either larger or smaller than the gears 6 and 7, thereby either increasing the speed of the machine or decreasing if more power is needed.

Fig. 3 shows my machine as an exact duplicate of one side section of Fig. 1 with the gear-wheels 5^a left off, with the exception that an extra ratchet-socket would project from the outside of the center of gear-wheels 6, and the ratchet-body on the ratchet-wheel side can extend out longer, so that wheels 4^a, as shown in Fig. 1, could be used on them practically the same as they are used in Fig. 1, but could not be used in the backward movement of the machine unless the ratchets in ratchet sprocket-wheels on gears 6 and 7 were reversed.

The motor in the single shape would be used when the reverse or backward motion was not often needed.

Having described my invention, what I claim as new, and desire to secure by Letters Patent, is—

1. The combination of a rectangular frame;

bearing-axles secured crosswise in the front and rear ends of said frame; bearing-wheels loosely journaled on the front axle; rear bearing-wheels working on the rear axles; recessed oscillating wheels journaled in said frame in rear of the front bearing-wheels, said oscillating wheels provided near their periphery with radial slots; an axle secured in said frame in the rear of said oscillating wheels; a sprocket-wheel secured on each end of said axle; an axle secured in said frame immediately in rear of the last-mentioned axle; a cog-wheel, a ratchet-wheel and ratchet device secured on said last-mentioned axle; an axle secured in said frame immediately in rear of the last-mentioned axle; a cog-wheel, ratchet-wheel and ratchet device secured on last-mentioned axle; cog-wheels, sprocket-wheels and ratchet devices similar to those just described, secured to the inner faces of the rear bearing-wheels; strap 1^b, secured to the frame and bearing the rear axle 2^a; a lever 11^b, hinged to the axle of the oscillating wheels; a lock-bar 11 hinged in said lever and adapted to lock either of said wheels alternately; sprocket-chains having their ends secured to said oscillating wheels, passing forward over and under said sprocket-wheels, the ratchet devices on the left-hand side being so set that the operation of the lever drives the vehicle forward when the lock-bar is locked in the left-hand oscillating wheel, and the ratchet devices on the right-hand side set as to drive the vehicle backward when the lock-bar is locked in the right-hand oscillating wheel, substantially as shown and described and for the purposes set forth.

2. The combination of a rectangular frame mounted on guide and drive wheels; axles secured in said frame; a series of cog and ratchet wheels and ratchet devices journaled on said axles on axles secured in said frame, and adapted to drive the drive-wheels; strap 1^b, bearing the rear axle; recessed oscillating wheels journaled on an axle secured in said frame, and provided near their periphery with radial slots; rollers journaled in the recess parts of said oscillating wheels; sprocket-chains passing over and under said sprocket-wheels, their ends passing over said rollers and into the recessed parts of said oscillating wheels; tightening devices securing the ends of said sprocket-chains; a lever hinged on the last-mentioned axle, and a lock-bar hinged to said lever and adapted to lock either of said oscillating wheels, said lever provided with means for guiding said front bearing-wheels, substantially as shown and described and for the purposes set forth.

3. In a lever-motor as shown, the combination of the frame 1; guide and drive wheels 4; cog and sprocket wheels journaled in said frame; ratchet devices secured to said cog and sprocket wheels adapted to drive said drive-wheels; recessed oscillating wheels 9, jour-

naled in said frame, and provided with radial slots 9^f; sprocket-chains 12 secured to said oscillating wheels 9, and passing over and under said sprocket-wheels; a lever 11^b, hinged to the axle of said oscillating wheels; a lock-bar 11, hinged in said lever and adapted to alternately lock either of said oscillating wheels; crank-handle 11^a, adapted to operate said lock-bar; an extension journaled on the upper end of said lever 11^b, and provided with arms 11^f; slotted arms 11^e, hinged to said arms 11^f; a bar 3^a, rigidly secured to the axle of

the guide-wheels, the ends passing through the slots in said arms, and a cap removably secured to the extension 11^e, and arms 11^f, secured in said cap, whereby said guide-wheels may be guided, substantially as shown and described and for the purposes set forth.

In testimony whereof I affix my signature in presence of two witnesses.

STEPHEN McCLELLAN.
